UNITED STATES PATENT OFFICE.

CHARLES S. BARNARD AND EDWARD A. BARNARD, OF WEST MERIDEN,
CONNECTICUT.

DESIGN FOR CALL-BELLS.

Specification forming part of Design No. 6,895, dated September 30, 1873; application filed September 5, 1873.
[Term of Patent 14 years.]

To all whom it may concern:

Be it known that we, CHARLES S. BARNARD and EDWARD A. BARNARD, of West Meriden, in the county of New Haven and State of Connecticut, have invented a new Design for Call-Bell; and we do hereby declare the following, when taken in connection with the accompanying drawing and the letters of reference marked thereon, to be a full, clear, and exact description of the same, and which said drawing constitutes part of this specification, and represents a side view.

This invention relates to a design for that class of call-bells in which the bell is struck by means of a piston passing through the axis of the bell; and it consists in the figure of a child or person standing beneath the bell, holding a hammer in its hand, as in the attitude of striking the bell. The mechanism, which is no part

of this design, is arranged so as to impart a movement to the hammer to give the blow.

A is the bell, supported upon a yoke, B, or in other convenient manner, the form of the bell being no part of the design. Beneath the bell, upon a suitable platform, a human figure, D, is arranged, holding the hammer in its hand, and in the attitude of striking the bell, as shown in the accompanying illustration.

We claim as our invention—

The design for call-bell, as shown in the accompanying illustration, and as herein described.

CHARLES S. BARNARD.
EDWARD A. BARNARD.
